J. W. Graham

UNITED STATES PATENT OFFICE.

JOHN W. GRAHAM, OF HINTON, WEST VIRGINIA.

TYPOGRAPHICAL OR SLUG-CASTING MACHINE.

1,220,094.

Specification of Letters Patent. Patented Mar. 20, 1917.

Application filed July 23, 1915. Serial No. 41,573.

To all whom it may concern:

Be it known that I, JOHN W. GRAHAM, a citizen of the United States, residing at Hinton, in the county of Summers and State 5 of West Virginia, have invented certain new and useful Improvements in Typographical or Slug-Casting Machines, of which the following is a specification.

My invention relates to typographical 10 machines, such as linotypes of the original construction, wherein circulating matrices are released from a magazine, in the order in which their characters are to appear in print, and then assembled in line together with expanding spacers, the composed line brought in contact with the face of a mold, the mold filled with molten metal, to form a line of type or slug against the face of the matrices, which produce the type characters thereon, 15 and the matrices thereafter returned to the magazines from which they were originally drawn.

More particularly it relates to that class 20 of machines having a series of magazines, in connection with means whereby any magazine of the series can be brought into operative position, and locked therein, and in which the magazines are housed in independent racks, and wherein the series of 25 magazines may be raised or lowered either by hand or power mechanism.

My invention is embodied in the new and 30 novel construction of the frame mechanism which supports the magazines, and particularly in the feature whereby the magazine in operative position stands projected forward, more than the other magazines of the series, and that this forward projection of the magazine is brought about by the circu- 35 lar travel of the magazine in being raised and lowered and not by any movement of the magazine after it arrives at the line of operative position, and this invention covers the feature that the magazines in their 40 travel change their relative position one to the other as they are moved up or down, and I also claim the feature whereby a dial is set for any desired magazine and the said magazine when it arrives in operative position, is automatically locked therein, and wherein the magazines are mounted on move- 45 able cam members which also guide the racks on their line of travel to exact operative position.

50 In the drawings I have shown my inven-

tion as an example, and in a preferred way, and I do not limit myself to any form or embodiment except in so far as such is specified in the claims.

Referring to the drawings, Figure 1 is a 60 side view of a portion of a linotype machine having my invention applied thereto. Fig. 2 shows a rear view of the forked arm A, having attached part of the raising and lowering mechanism. Fig. 3 shows the power 65 raising and lowering device. Fig. 4 shows a worm gear wheel having attached a cog gear wheel used in the raising and lowering device. Fig. 5 shows the automatic locking device. Fig. 6 shows part of the locking 70 device. Fig. 7 is a view of the cam or rack members which support the magazines. Fig. 8 shows a magazine housed in its rack. Fig. 9 is a side view of the parts shown in Fig. 8.

75 Referring to Fig. 1,

A is the forked arm of the machine.

A¹ is a grooved supporting member having a rack thereon which supports the magazines.

80

A² shows the pin on which the rack members A¹ are hinged.

A³ shows the arm which houses the locking device.

A⁴ shows the upright shafts used in connection with the power raising and lowering device.

A⁵ shows the cross shaft connecting the upright shafts A⁴.

A⁶ shows a pulley on the cross shaft A⁵.

A⁷ shows a casting to house the gear A⁹, and one end of the shaft A⁸.

A⁸ shows a shaft to raise and lower the magazines and has on it a crank.

A⁹ shows the worm gear "wheels which mesh into the threads of the shaft A⁸, and have immediately behind them as shown in Fig. 4 a cog gear wheel to mesh into the cog or rack surface of the rack members A¹.

A¹⁰ shows a slot in the member A¹, Fig. 7, 95 to receive rollers B² on the racks B which rollers may be fastened or secured in place by means of screws B³ passing through holes A¹¹, Fig.

B shows the rack which houses the magazine.

B¹ shows the dogs which hold the magazines in place (Fig. 8).

B² shows the rollers on the racks B 105 (Fig. 8).

110

- C shows the locking device.
- C¹ shows the crank to set the automatic lock. (See Fig. 5).
- C² shows the dial finger or pointer used in setting the lock (Fig. 5).
- C³ shows the dial.
- C⁴ shows a shaft having on one end a crank and on the other end the cog gear C⁵.
- C⁸ shows a shaft having on it a thread and also a cog gear C⁶.
- C⁹ shows a strap having in it a slot, and also a pawl which engages the thread on the shaft C⁸.
- C¹⁰ shows the lock pins.
- C¹¹ shows the holes in the frontal cams A¹ to engage the lock pins.
- D shows the casting which houses the pulleys and gears of the power raising device.
- D¹ shows the rollers of the power raising and lowering device.
- D² shows a cog gear used in the power raising and lowering device (Fig. 3).
- D³ shows a pulley used in the power raising and lowering device.
- D⁴ shows the pin on which the casting D is pivoted.
- D⁵ shows a lever.
- D⁶ shows a pulley already on all machines of the class described.
- E shows the channel entrance.
- F shows the escapement channel, the lower edges of the entrance and escapement channels being substantially in alinement with the pivots A².
- M shows the magazines.
- In operating the machine any of the magazines can be brought into operative position by turning the crank on the shaft A⁸. When the said shaft is turned it operates the worm gear wheels A⁹, and the cog gears immediately behind, and the cog gears are intermeshed with the cogged surface of the supporting members and thus raise or lower the magazines.
- In operating the power device, the lever D⁵ at normal position holds both of the rollers D¹ free of the wheel D⁶. The said lever can be moved so as to bring either of the rollers D¹ into contact with the wheel D⁶, thus operating the shaft A⁵ and its connected shafts A⁴ in either direction, and the shafts A⁵ and A⁴ and A⁸ being connected by bevel gears, the magazines are thus raised or lowered.
- To operate the locking device, the crank C¹ is turned until the finger C² stands at desired number on the dial. The dial is numbered to correspond with the magazines, in this instance, 1, 2, 3, 4, and 5. The slide C⁹ is made of a thickness, such that the lock pins that rest on it do not protrude through the piece A², but the said slide is made near the center with a depression just wide enough to receive the head of one pin. When the said depression is set under any desired pin the said pin can drop into its corresponding hole in the supporting member A¹, when the said cam A¹ is moved a sufficient distance to bring the said hole to position, but the other pins C¹⁰ having their heads resting on the thicker portion of the slide C⁹, cannot protrude into the holes C¹¹ in the supporting members A¹. The pins C¹⁰ are individually pressed inward by any desired spring mechanism, not shown. The gears on the shafts C⁸ and C⁴, and the thread on the shaft C⁸, which engages the pawl on the slide C⁹ are so arranged that when the finger C² is brought to any desired number, the depression on the slide C⁹ is moved to the pin which corresponds with the magazine whose number is designated on the dial C³ by the finger C². As soon as the finger on the dial is moved to a new number the magazines are unlocked, and the slide moves with its depression to a new pin and as it moves it withdraws the pin already engaged.
- It is to be noted that the points of support of the several magazines as well as the lock pin holes are closer together near the center than at the top and bottom when measured along an arc. This permits a greater number of magazines to be supported in a device of this general construction than could be obtained if the distances between the magazine racks were made equal.
- Having described my invention, its construction and operation, what I claim and desire to secure by Letters Patent of the United States, is as follows:
1. In a typographical machine, the combination of a plurality of removable magazines, a series of superimposed independent racks therefor and substantially vertically disposed members having points of support for said racks, said points being set closer together near the center of the series than at the top and bottom of said series.
  2. In a typographical machine, the combination of a plurality of removable magazines, racks therefor, points of support for said racks set closer together near the center of the series than at the ends, supporting members for said racks and magazines, each having a cogged surface, and cog gear wheels intermeshing with the said cog surfaces of the supporting members.
  3. In a typographical machine, the combination of a plurality of removable magazines, racks therefor, points of support for said racks set closer together toward the center of the series than at the ends, supporting members for the racks, each having a cogged surface, cog gears intermeshing with the said cog surface of the supporting members, and worm gear wheels attached to the said cog gears.
  4. In a typographical machine, the combination of a plurality of removable magazines, racks therefor, points of support for said racks set closer together near the center of the series than at the ends, supporting members for the racks, each having a cogged surface, cog gears intermeshing with the said cog surface of the supporting members, and worm gear wheels attached to the said cog gears.

- nation of a plurality of removable magazines, racks therefor, points of support for said racks set closer together toward the center of the series than at the ends, supporting 5 members for the racks, each having a cogged surface, cog gears intermeshing with the said cog surface of the supporting members, worm gear wheels meshing with certain of said cog gears, a shaft for the said worm 10 gears, and means to operate the shaft to raise or lower the magazines.
5. In a typographical machine the combination of a plurality of removable magazines, independently supported racks therefor, having their points of support nearer together at the center than at the ends of the series when measured on an arc, curved supporting members to support the said rack, and the frontal pair of the said supporting 15 members fitted with holes, each hole being laid off at a different distance from the center on which the said supporting member is hung, and a series of lock pins to engage the said holes.
- 20 6. In a typographical machine the combination of a plurality of magazines, racks therefor, curved supporting members to support said racks, said supporting members being fitted with holes, each hole being laid off at a different distance from the central longitudinal line of said supporting member, a series of pins to engage said holes, and a carrier movable under the heads of said pins, having a depression to receive the head of 25 one pin corresponding to the rack in operative position.
7. In a typographical machine, the combination of plurality of magazines, racks therefor, front and rear supporting members to support said racks, the front supporting member being fitted with holes laid off at a different distance from the center on which the said supporting member is hung, a series of pins to engage said holes, a slide movable 30 under the heads of said pins, and having in it a depression to receive the head of one pin, a tooth connected to said slide, and a shaft having a thread engaged with the said tooth.
- 35 8. In a typographical machine, the combination of a plurality of magazines, racks therefor, supporting members to support said racks fitted with holes, pins to correspond with the said holes, a slide moving under the heads of the said pins, and having 40 a depression to receive the head of one pin, and means for moving said slide a predetermined distance to lock a desired magazine in operative position.
- 45 9. In a typographical machine the combination of a plurality of magazines, racks therefor, supporting members to support said racks fitted with holes, pins to correspond with the said holes, a slide moving under the heads of the said pins, and having 50 a depression to receive the head of one pin, means for moving said slide a predetermined distance to lock a desired magazine in operative position, said means including a dial having graduations to correspond with the number of magazines, and a movable finger adapted to be set to any of said graduations.
- 55 10. In a typographical machine the combination of a plurality of removable magazines, set in independent racks, the racks being set closer together near the center of the series, front and rear supporting members to support the said racks, the front supporting member fitted with holes, each hole being laid off at a different distance from the center on which the said supporting member is hung, a series of pins to engage the said holes, a slide movable under the heads of the said pins and having in it a depression large enough to receive the head of one pin, a pawl connected to the said slide, a shaft having a thread engaged with the said pawl, a dial having graduations to correspond with the number of magazines connected to the said shaft, a movable finger fixed to a hand wheel which can be set at any of the said graduations, and the whole so arranged that when the dial is set at any desired number the depression in the slide seats under the head of the pin corresponding with the hole in the supporting member, which corresponds with the desired magazine.
- 60 11. In a typographical machine the combination of a plurality of superimposed magazines, racks therefor, front and rear vertically disposed members for said racks, a cogged surface being provided on the said members, cog gears engaged with the said cogged surface of the members, worm gears coacting with said cog gears, shafts having threads engaged with the said worm gears, and means by which the said shafts can be operated to raise and lower the magazines carried by said members.
- 65 12. In a typographical machine, the combination of a plurality of superimposed magazines, and racks therefor, front and rear members to support said racks, a cogged surface being provided on said members, gear wheels engaged with the cogged surface of said members, means for turning said gear wheels including geared shafts to raise and lower the front and rear ends of the racks simultaneously, and a locking device to lock any desired magazine when it is moved into operative position.
- 70 13. In a typographical machine the combination of a plurality of magazines, racks to support said magazines, rollers affixed to the said racks, members each made with a cogged surface and having a slot to receive the said rollers on the racks and means coacting with the rollers in said slots for holding the magazines in place.

14. In a typographical machine the combination of a plurality of magazines, racks to support said magazines, rollers affixed to the said racks, supporting members made with cogged surface and having a slot and holding means to receive the said rollers on the racks and holding the same in place, said supporting members being pivoted at points substantially in alinement with the bottom edges of the entrance and escapement channels, gear wheels intermeshing with the cog surface of the said members, and worm gear wheels attached to the said cog gear wheels.

15. In a typographical machine the combination of a plurality of magazines, racks to support said magazines, rollers affixed to the said racks, supporting members made with cogged surface and having a slot and holding means to receive the said rollers on the racks and hold the same in place, said supporting members being pivoted at points substantially in alinement with the bottom edges of the entrance and escapement channels, cog gear wheels intermeshing with the cog surface of the said members, worm gear wheels attached to said cog gear wheels, and shafts having threads engaging said worm gear wheels.

16. In a typographical machine the combination of a plurality of magazines, racks to support said magazines, supporting members made with cogged surface, screws passing through said members and engaging the racks to hold the magazines in place thereon, said supporting members being pivoted at points substantially in alinement with the bottom edges of the entrance and escapement channels, cog gear wheels intermeshing with the cog surface of said members, worm gear wheels attached to said cog gear wheels, shafts having threads engaged with said worm gear wheels, and means to simultaneously operate both of the said shafts.

17. In a typographical machine the combination of a plurality of magazines, racks for said magazines, front and rear supporting members to support the said racks, the

frontal supporting members being fitted with holes, lock pins to engage said holes, and the said holes being each laid off at a different distance from the center on which the said supporting members are hung.

18. In a typographical machine the combination of a plurality of magazines, racks for said magazines, front and rear members to support said racks, the front member being fitted with holes, lock pins to engage the said holes, a slide movable under the heads of the said lock pins having a depression to receive the head of one pin, a pawl connected to the said slide, and a shaft having a thread engaged with the said pawl.

19. In a typographical machine the combination of a plurality of removable magazines, racks for said magazines, supporting members to support said racks, said supporting members being fitted with holes, lock pins to engage the said holes, the said holes being each laid off at a different distance from the center on which the said cam members are hung, a slide movable under the heads of said lock pins, there being a depression in the said slide to receive the head of one pin, a pawl connected to said slide, a shaft having a thread engaged with the said pawl, a dial having graduations corresponding with the number of magazines, connected to the said shaft, a hand wheel carrying a finger which can be set to any of said graduations, and means whereby when said finger is set at any desired number the depression in the slide is brought to rest under the pin corresponding with the hole in the supporting member, which corresponds with the desired magazine and the desired magazine is automatically locked when brought to operative position.

In testimony whereof I affix my signature in presence of two witnesses.

JOHN W. GRAHAM.
